MECHANICAL DANCING DOLLS

Clifford L. Williams, Rocklin, Calif.

Application March 3, 1958, Serial No. 718,885

7 Claims. (Cl. 194—12)

The present invention generally relates to an amusement device and more particularly to a mechanical doll construction which incorporates a plurality of dancing dolls which are operated in unison with a record player whereby the dolls will dance in accompaniment to the music being played.

An object of the present invention is to provide a dancing doll construction which is mechanically operated by a rotatable shaft driven by a motor which is coin controlled and is stopped in response to completion of a record played by the record player.

A further object of the present invention is to provide a construction in accordance with the preceding object in which the rotatable shaft is provided with a plurality of serrated gears or plate members thereon in engagement with pivot levers which suspend the dancing dolls thus causing the dolls to dance when the shaft is rotated.

Another important feature of the present invention is to provide mechanical dancing dolls which are incorporated in an enlarged casing which also incorporates a record player therein.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of the construction of the present invention illustrating the housing with the mechanical dolls therein;

Figure 2 is a longitudinal, plan sectional view illustrating the relationship of the record player and mechanical dancing dolls;

Figure 3 is a detailed sectional view taken substantially upon a plane passing along section line 3—3 of Figure 2 illustrating the record player and the relationship of the tone arm to the trip lever for stopping the dancing dolls;

Figure 4 is a detailed sectional view taken substantially upon a plane passing along section line 4—4 of Figure 2;

Figure 5 is a fragmental sectional view taken substantially upon a plane passing along section line 5—5 of Figure 2;

Figure 6 is a detailed sectional view taken substantially upon a plane passing along section line 6—6 of Figure 2 illustrating the coil controlled operating mechanism; and

Figure 7 is a schematic view illustrating the wiring diagram for operation of the device.

Referring now specifically to the drawings, the numeral 10 generally designates the casing in which the mechanical dancing dolls of the present invention are housed and the casing 10 includes a bottom wall 12, an upstanding rear wall 14, a top wall 16, end walls 18 and 20, a transparent front panel portion 22 and a pivotal

2

front panel portion 24 which cooperate to form the front wall of the cabinet or casing. The bottom wall 12 is provided with depending supporting legs 26 of any suitable length for supporting the casing 10 in any desired position. The casing is also divided into two sections by a transverse partition wall 28 disposed in mutually spaced relation to the end walls 18 and 20 and in parallel relation thereto. The transparent panel 22 is provided with a peripheral frame 30 for mounting the same in the front of the compartment to one side of the partition 28 while the pivotal panel 24 is hingedly mounted at the bottom by hinge pins 32 and retained in closed position by a latch mechanism 34 with there also being provided a retainer chain 36 which limits the downward swinging movement of the panel 24. The panel 24 is also provided with an opening 38 having a screen or cloth member 40 therein with a speaker assembly generally designated by the numeral 42 disposed therebehind whereby sound produced by the speaker 42 will pass through the opening 38. Also provided in the pivotal panel 24 is a coin slot 44 for a purpose described hereinafter.

Mounted on the bottom wall 12 within the compartment defined by and between the end wall 18 and the partition wall 28 is a record player assembly generally designated by the numeral 46 and which may be of any suitable and conventional construction with there being provided the usual turntable 48 and tone arm 50 which carries the pick-up needle or stylus 52. The turntable 48 carries the usual circular plate type record 54 and the record player 46 may be of the type which will play automatically a plurality of records or it may be of the single playing type with the tone arm 50 being automatically operated so that when the record has completed playing, the tone arm will be disposed adjacent the center of rotation thereof and by the usual mechanism, the tone arm will be lifted and swung outwardly to a normal position after which the free end thereof drops down to an at rest position. The tone arm 50 is provided with an upstanding pin 56 for engaging the spring urged trip lever 58 position. The tone arm 50 is provided with an upstanding pin 56 for engaging the spring urged trip lever 58 mounted on a bracket 60 by a pivot pin 62. A spring 64 interconnects the other end of the lever 58 and the bracket 60 for urging the lever 58 with the bottom free edge towards the center of the record 54 whereby swinging movement of the tone arm 50 in the elevated position towards a position outwardly of the edge of the record 54 will cause the pin 56 to engage the bottom of the lever 58 thus swinging the same towards the partition 28 and as the tone arm 50 drops down to the at rest position, the pin 56 will be disengaged from the lever 58. The free end of the lever 58 is provided with an elongated flexible member 66 which extends upwardly and proceeds through an eye member 70 mounted on the top wall 16 of the casing 10. The other end of the string 66 is attached to one end of an elongated lever 72 by virtue of an attachment bracket 74. The lever 72 is supported adjacent the center on a pivot pin 76 and is provided with a movable switch contact 78 and also a metallic block 80 which is capable of being attracted by a stationarily mounted magnet 82. The magnet 82 is supported on a shelf member 84 and also supported on the shelf member 84 is a stationary switch contact 86 which is adapted to be engaged by the movable contact 78 when the end of the lever 72 having the string 66 attached thereto is moved downwardly. A coin chute or tube 88 is supported within the casing and has a discharge end immediately above the inner end of the lever 72 wherein coins 90 discharged from the chute 88 will fall directly on the upper surface of the lever 72.

72 thus pivoting the inner end thereof downwardly for urging the block of ferrous material 80 into contact with the magnet 82 and moving the movable contact 78 into engagement with the stationary contact 86 thus completing the electrical circuit from the conductor 92 attached to the movable contact to the conductor 94 connected with the stationary contact 86. The switch contacts 78 and 86 will be retained in position as long as the magnet 82 retains the block 80 against the under surface thereof thus retaining the lever 72 with the inner end thereof pivoted downwardly. After the record has completed playing and the tone arm automatically moves back towards the outer edge of the record, the pin 56 on the tone arm 50 will engage the trip lever 58 moving the bottom end thereof towards the partition 28 thus pulling on the string 66 and causing the inner end of the lever 72 to be moved upwardly thus disengaging the metallic block 80 from the magnet 82 and disengaging the movable contact 78 from the stationary contacts 86 thus breaking the circuit between the electrical conductors 92 and 94. Also disposed in underlying relation to the inner end of the lever 72 is a coin box 96 supported by hooks 98 thereon detachably engaged with supporting brackets 100.

Mounted rearwardly of the record player construction 46 is an upstanding bracket 102 having an electric motor 104 supported thereon with the drive shaft 106 extending vertically and having a circular friction plate 108 mounted thereon for rotation about a vertical axis. The motor 104 is energized when the contacts 78 and 86 are in engagement with each other. An elongated shaft 110 extends through the partition 28 and is journaled in a bearing bracket 112 on the rear wall 14 and a bearing bracket 114 on the end wall 120. The inner end of the shaft 110 is provided with a circular friction disk 116 having the periphery thereof in frictional driving engagement with the upper surface of the friction plate 108 whereby driving force from the motor 104 will be transmitted to the shaft 110 thus rotating the shaft 110 about its longitudinal axis.

Disposed in longitudinally spaced relation on the shaft 110 is a plurality of rotatable gear or serrated plate members 118. Disposed in spaced relation to the shaft 110 is an elongated support bar 120 having upstanding pairs of lugs 122 supported thereon. Disposed between the pairs of lugs 122 is a pair of pivot levers 124 extending to one side of the support bar 120. The free end of the levers 124 is in engagement with one of the serrated members 118 with a spring 126 being connected between the free end of the lever 124 and the support bar 120 thus retaining the free end of the lever 124 in engagement with the serrated wheel or member 118 whereby rotation of the member 118 will cause oscillation of the lever 124 about the pivot pin 120 which mounts the lever 124 on the bracket lugs 122. The outer end of the lever 124 is provided with a depending flexible string 130 to which is attached and supported a pair of dancing dolls 132 of any suitable configuration with the flexible line 130 being divided in any suitable manner whereby the dancing dolls will act substantially as puppets and will dance in accordance with oscillation of the lever 124. Other of the levers which are designated by the numeral 134 have the free ends thereof pivoted to the lugs 122 by a pivot pin 136 and these levers extend in overlying relation to other of the rotatable serrated members 118 and include a reversely bent spring tang or spring member 138 in engagement with the serrated wheel for oscillation of the levers 134 in the same manner as levers 124 but with the levers 134 being gravity urged into engagement with the rotatable wheels 118. The levers 134 are also provided with flexible strings 140 suspending dolls 142 which are in the form of persons making music.

The front of the compartment which has the panel 22 may be provided with a light 144 of any suitable construction which may be of the fluorescent tube type light

with there being a reflector 146 above and forwardly of the same for reflecting the light directly onto the dancing dolls 132 and 142. Thus with the present invention, the operation of the dancing dolls is coin controlled and by dropping the coin on the lever 72, the movable contact 78 will be brought into contact with the stationary contact 86 and the magnet 82 will hold this contacting relation for driving the shaft 110 through the motor 104. Rotation of the shaft 110 will cause agitation or oscillation of the levers 124 and 134 thus causing dancing or agitation of the dolls or puppets 132 and 142. When the record is completed, the tone arm will lift and swing outwardly and engage the pin 56 with the trip lever 58 for stopping the shaft 110 by pulling the movable contact 78 away from the stationary contact.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. A mechanical dancing doll assembly comprising a casing having a transparent front panel, an elongated support bar disposed rearwardly of the transparent panel and generally in parallel relation thereto, a rotatable shaft disposed substantially parallel and adjacent to said bar, a plurality of levers pivotally mounted on said bar and having one free end extending remotely therefrom, means on said shaft for engagement with said levers for causing oscillation of said levers upon rotation of the shaft, and means on each of said levers for supporting a doll therefrom whereby oscillation of the levers will cause dancing movement of the dolls, said means for supporting the dolls including flexible strings for suspending the dolls behind the transparent panel for permitting oscillation thereof.

2. The combination of claim 1 wherein illumination means is provided for the dancing dolls.

3. The combination of claim 1 wherein said means on said shaft for engaging the levers includes a plurality of longitudinally spaced serrated circular plates, certain of said levers being spring urged into engagement with certain of said serrated plates, and other of the levers being gravity urged into engagement with other of said serrated plates.

4. The combination of claim 1 together with means for rotating said shaft.

5. The combination of claim 4 wherein said means for rotating said shaft includes an electric motor, coin controlled switch means for energizing said motor, said switch means including a pivotal lever having a movable contact thereon, a stationary contact mounted on support means, a coin tube disposed adjacent one end of said lever for discharging coins onto the lever for causing temporary unbalance of the lever for movement of the movable contact into engagement with the stationary contact for energizing the motor, and magnetic means holding the movable contact in contact with the stationary contact, said magnetic means being rendered ineffective in response to completion of the playing of a record on a record player.

6. The combination of claim 5 wherein said magnetic means includes a permanent magnet mounted on a support and a block of ferrous material mounted on the lever whereby the magnet will hold the lever in contact closing position, a flexible string connected with the lever on the opposite side of the pivot support for the lever from the block of ferrous material whereby movement of the flexible string in an upward direction will cause movement of the ferrous block away from the magnet thus moving the contacts in remote relation, said string being connected to a pivotal trip lever, said trip lever being

mounted on a support and disposed in the path of movement of a projection on the tone arm of a record player thus moving the movable contact away from the stationary contact when the tone arm of a record player returns to an inoperative position after completion of a record.

7. In combination with a record player having a tone arm automatically moved back to a normal position after the record has been played, a series of dancing dolls, means for supporting and agitating said dolls, said means

5

being driven by a coin controlled electric motor, and means responsive to movement of the tone arm of the record player back to a normal position for stopping the electric motor and dancing dolls.
